UNITED STATES PATENT OFFICE.

SAMUEL P. FRALEY, OF COLUMBUS, OHIO, ASSIGNOR OF ONE-HALF TO
JAMES H. NEIL, OF SAME PLACE.

BROOM-MACHINE.

SPECIFICATION forming part of Letters Patent No. 308,888, dated December 9, 1884.

Application filed April 25, 1882. Renewed February 15, 1884. (No model.)

To all whom it may concern:

Be it known that I, SAMUEL P. FRALEY, of Columbus, in the county of Franklin, State of Ohio, have invented a new and useful Improvement 5 in Machines for Making Brooms, which improvement is fully set forth in the following specification and accompanying drawings, in which—

Figure 1 is a side elevation of my improved 10 broom-machine. Fig. 2 is a plan or top view through line *x* of Fig. 1, showing the bed of the machine. Fig. 3 is a front view of the upper part of the machine. Fig. 4 is an isometric view, with part cut away, showing arrangement of bed guideway and mechanism for 15 operating the wire benders and clinchers. Fig. 5 is an enlarged perspective view, partly cut away, showing construction of the device for bending and clinching the wires on the broom-brush. Fig. 6 is a perspective view of the boxing 20 for the front end of the bending and clinching device, containing the clutch for holding the rotating wire-benders. Fig. 7 is an end view of guide-bed and boxing for the bending 25 and clinching device through line *Z* of Fig. 1. Fig. 8 is a rear end view of the complete machine, showing construction of the compressing-levers. Fig. 9 is a perspective view of 30 the lower clamp or die, in the groove of which the binding-wires are laid preparatory to placing the broom therein. Fig. 10 is a perspective view of the upper and lower clamps or 35 dies, with a broom compressed between and the projecting ends of the binding-wires crossed by the bending-fingers; and Fig. 11 a horizontal sectional view of the arm or standard of the machine through line *y* of Figs. 1 and 3.

The object of my invention is to provide a 40 machine for manufacturing the wire-bound brooms for which I have obtained Letters Patent. Said brooms consist in having wires laid across the straw of the broom and bent around and clinched on the opposite sides to hold the straw, instead of sewing the broom, 45 as is usually the case.

The design in this machine is to clamp the broom between suitable dies and afterward to bend and clinch the protruding ends of the tie-wires around the straw.

50 The invention consists in having an upper and a lower die, which, when placed together,

form within the exterior shape of the broom. The lower die is secured permanently in one position to the bed-plate, and the upper die is secured to a plunger which works between 55 guides, and is capable of being vertically moved to and from the lower stationary die. Two parallel transverse grooves are formed across each of these dies to receive the tie-wires, and each die is also provided with recesses by the 60 sides of these grooves. The projecting ends of the tie-wires are then approached by suitable fingers, which partially bend the ends of the tie-rods past each other, and other mechanism is then employed to force the bent ends 65 down on the opposite sides of the broom-straw and clamp them firmly, all of which will now be described in detail.

In the accompanying drawings, A represents the base of the machine, preferably cast. 70 At the rear end is a standard bracket or arm, B, which projects upward a suitable distance and extends forward to a point near the center of the base. In the front face, C, of this bracket is a grooved guideway, C', preferably dovetailed, as shown in Fig. 11, to receive a dovetailed plunger, D, which slides vertically therein.

To provide for wear I have made the groove C' wider than the plunger, and somewhat tapering, so that the upper end of the groove is slightly wider than the lower end. A wedge-key, D', is then inserted in the groove by the side of the plunger, and a screw or bolt, D", which passes through a bracket in the upper 85 end of the wedge D' and into the bracket, enables the operator to raise or lower said wedge and tighten or loosen the plunger in the groove. The upper end of the plunger is hinged to an arm, E, which arm extends to the rear of the 90 machine. Centrally the arm is pivoted to a link, E', which is hinged to the machine-bracket B on top.

On the rear end of the arm E is a ball, F, which enters a socket, F', in the upper end of 95 the vertical bar or rod G. The upper end of the rod or bar G is screw-threaded, as shown at G', and this enters a screw-threaded aperture in the lower side of the socket F'. A nut, G'', may be employed to make the socket vertically adjustable on the rod G. The lower 100 end of the rod G is hinged to a joint, H, and

the opposite end of this joint has also a ball, H', which operates in the stationary socket H" on the frame. The ball H' is also adjustably connected with the joint H by means of 5 the screw-threaded part I and nut I'. A vertically-disposed lever, J, is permanently attached to or cast with the joint H, and when the plunger D is elevated this lever rests in a position near the rod G, or parallel therewith, 10 and is held there by means of a hook, J', attached to the rod G. The rod G and joint H thus form a toggle-joint, and when the lever J is drawn forward and the pivot J" is on a line with the ball-and-socket joints F' H' the plunger 15 D will have reached its lowest limit, and will remain in this position until the operator desires to return the plunger. By means of the screw-threaded ends I G' the limit of the plunger may be regulated. The lower end of 20 the plunger D is provided with a die, L', inverted, similar to the upturned lower die, L, as shown in Fig. 9.

The upper face, A', of the bed of the machine, beneath the head of the bracket B, is 25 provided with a plate, K, having its longitudinal edges or sides K', Fig. 4, beveled. The interior, K'', of this plate is cut away, as fully shown in Fig. 4, to receive the mechanism which operates the wire-bending fingers. Centrally on this plate the lower die, L, is secured by means of bolts L' through the ears L''. On each side of this die is a carriage, M, adapted to have its ends M' embrace the opposite beveled edge of the guideway K beneath. 30 The carriages M thus slide on the guideway to and from the die L.

The carriage is placed across the guideway at an angle equal to the angle of the side of the die L which each carriage approaches. 40 At both ends of each carriage is a boxing, N, and between these boxings and journaled therein is a rocker-shaft, O. This rocker-shaft has centrally an aperture, O', which passes through from end to end to receive a plunger, P. The forward end of this plunger has a lever, P', attached thereto, and said lever is in turn hinged to a fulcrum, P'', on the boxing N, so that when the lever P' is raised or lowered the plunger P will move endwise 45 a limited distance in the rocker-shaft.

Q Q' represent fingers pivoted side by side centrally to the side of the rocker-shaft O. The ends of these fingers enter suitable recesses in the rocker-shaft and embrace the 55 plunger P. The opposite projecting ends of these fingers are crossed in the form of a pair of shears. The approaching edges of these fingers have shallow rounding grooves Q'', the object of which will be hereinafter explained. 60 The rocker-shaft is provided near each end with a pair of these hinged fingers, and at the points that their inner ends embrace the plunger P are inclined surfaces Q''' on both sides, so that when the plunger is moved inwardly the inclined surfaces Q''' will cause the 65 inner ends of the fingers Q Q' to recede from each other, and correspondingly cause the

outer ends to approach each other. On the opposite side of the rocker-shaft O from the locations of these hinged fingers are stationary 70 fingers R. These fingers project from the shaft and diverge from each other, one of them projecting upwardly, the other downwardly. Two of these diverging fingers are located on the shaft at one end by the side of each other, 75 and the other two at the opposite end of the shaft. The faces of these fingers are also provided with shallow rounding grooves R'. The shaft O has at the forward end a head or flanges, S, which projects above and below the bulk of the shaft O, and each flange is provided with an aperture, S'. The forward boxing is also provided with an enlargement, T, above the journal of the rocker-shaft, through which is placed horizontally a key-catch or latch-piece, T', the inner end, T'', of which is adapted to enter the apertures S' of the rocker-shaft. When the latch-piece T' is drawn out, the shaft O can be turned half-way round, so that the latch will engage with the 80 aperture S' on the opposite side.

The object of turning the rocker-shaft is to enable the operator to adjust either the stationary fingers against the wires in the dies or to use the hinged fingers Q Q' on the opposite 95 side, as will be more fully explained hereinafter. By reference to Fig. 4 it will now be seen how the carriage M containing this rocker-shaft O is moved to and from the die L.

Beneath the die, and hinged to the plate under the die L, or to a cross-piece in the guideway K, is pivoted centrally a cross-lever, U, to the opposite ends of which, within the recess K'' of the guide-plate K, are hinged the links V. These links diverge from each other, 105 the end of one being hinged to the under side of the carriage M on one side of the die L, and the other link hinged to the carriage on the opposite side of the die.

Projecting out from one side of the cross-lever U is an arm, U', to which is hinged a joint, W, and to this joint is hinged a link, W', the forward end of which projects through the side of the bed A, and is attached to an arm, X, on the horizontal shaft X' on the outside of the bed A. The opposite end of the shaft X' has a vertically-disposed lever, X''. When this lever is drawn forward, the intermediary mechanism above described causes the carriages M to travel toward the die L.

The dies will now be described in detail: The lower die, which for all purposes is substantially the same as the upper die, will only be described. The die is formed preferably as shown, to represent the shape of a broom. 115 It has three depressed surfaces, a, b, and c. At the forward end is a convex surface, f, designed to receive the handle. At a point equal to one-third of the distance across the face of the die is a ridge having therein a groove, d, 120 and at a point equal to about one-half the distance between this groove and the rear end of the die is a similar parallel groove, e, on a ridge. These grooves are semicircular de-

pressions, and are designed to receive the tie-wires for binding the broom.

The depressed surfaces *a b c* represent the bulge of the broom, and it is obvious that by 5 causing the broom to receive a heavy pressure between the dies thus constituted every broom will receive a like pressure, and a similarity will exist between the brooms thus made and greatly enhance their marketable values.

10 At one end of the ridges containing the grooves *d e* are recesses *g*, extending inwardly a short distance by the side of the grooves, and on their opposite ends are similar recesses, *h*, but on the opposite side of the groove. 15 The object of these recesses is to permit the ends of the tie-wires to pass through and clasp on the opposite side of the straw. A somewhat larger recess, *i*, is formed in the side of the die, at the end of each groove *d e*, to permit the bending-fingers of the rocker-shaft to enter.

j j represent guard-arms, which are secured to the sides of the lower die, near the rear end, and project upwardly a short distance 25 above the face of the die.

k k are similar guard-arms, secured to the sides of the lower die midway between the forward and rear ends. The upper die, *L'*, has only the two downwardly-projecting arms 30 *l l*, located near the rear end, so that when the

two dies are clamped together they pass down on opposite sides of the lower die next to the rear guard-arms, *j j*, as shown in Fig. 10. The forward end of the die on one side of the 35 handle-rest *f* has a shield, *m*, which extends back to the cross-groove *d*. This shield is the same height as the guard-arms *j k*. The upper die, *L'*, is also similarly provided with this shield *m*. It will thus be observed that

40 when the two dies are clamped together the sides are wholly inclosed, so that no part of the broom-brush is exposed except the protruding end and the spaces between the guard-arms *j k l* and shields *m*.

45 *n* represents one of the tie-wires, which is simply a straight piece of suitable wire. This is laid in the groove *d* next to the handle. The tie-wire *o* which rests in the rear groove, *e*, is somewhat longer than the wire *n*, and has 50 hooked or upturned ends *p*. The object of this is to prevent the straw in the broom from being crowded together after the wire is bent and pressed into position.

The operation is as follows. The machine 55 as shown in Fig. 1 is in position to receive the broom. The straw is first bound to the handle in the ordinary manner. It is then ready to be placed in the machine. The tie-wires *n o* are first laid in their respective 60 grooves, with the bent ends of the rear wire, *o*, upturned. Similar tie-wires are also placed in the grooves in the upper die, with the single exception that the bent ends of the wire are turned down. Springs or clasps in the grooves 65 of the upper clamp (not shown) hold the wires from falling out. The broom is then laid on the lower die, with the handle resting in the

recess or ledge *f*. The lever *J* is now brought into requisition and drawn forward, causing the plunger *D* to descend, tightly compressing the broom between the die-heads, as shown in Fig. 10. The toggle-jointed levers *G H* hold the dies in this position.

70 As shown in Fig. 2, the stationary diverging fingers on the rocker-shaft are in position to approach the protruding ends of the tie-wires *n o*. To bend them into the position shown in Fig. 10, the lever *X''* is drawn forward, which moves the carriage *M* toward the die. The diverging fingers *R* therefore strike 75 the ends of the tie-wires and cross them, after which the carriages *M* are caused to recede from the dies, and the latch *T* drawn forward to disengage the end *T''* from the head *S*. The shaft *O* is then rotated, so that the hinged fingers *Q Q'* 80 appear in the position formerly occupied by the stationary fingers *R*. The lever *X''* is again drawn forward, which moves the carriages *M* up to the dies, and as the fingers *Q Q'* strike the partially-bent ends of the tie-wires *n o* they 85 are forced back through the recesses *g h* on opposite sides of the straw. The handle *P'* is then raised, which drives in the plunger *P* and causes the outer ends of the hinged fingers *Q Q'* to move toward each other and 90 tightly clamp the ends of the wires between them.

95 What I claim as new, and desire to secure by Letters Patent, is as follows:

1. An upper and lower die for compressing, 100 forming, and holding the broom in the process of manufacture, provided with grooved ridges to receive the tie-wires, and having depressed surfaces between the said ridges and the raised outer edges, substantially as and for 105 the purpose herein shown.

2. In a machine for forming, compressing, and holding brooms, a plunger carrying the upper die, in combination with the lever *E*, link *E'*, toggle-jointed levers *G H*, and operating-lever *J*, substantially as and for the purpose herein shown.

3. The die-heads *L L'*, having the grooved ridges *d e*, recesses *g h i*, guard-arms *j k l*, and shields *m*, substantially as and for the purpose 115 shown.

4. The bed *A*, having the guideway *K*, in combination with the lower die, *L*, placed thereon centrally, as shown, having the grooved ridges *d e*, parallel with the said guideway, substantially as and for the purpose shown.

5. The bed *A*, having the guideway *K*, in combination with the carriages *M M*, on opposite sides of the lower die, carrying a rocker-shaft, *O*, having the diverging fingers *R* on one 125 side and the hinged fingers *Q Q'* on the opposite side, and with the die *L*, substantially as herein shown.

6. The carriage *M*, provided with the box *N*, in combination with a rocker-shaft, *O*, 130 having the diverging fingers *R R* on one side, substantially as and for the purpose herein set forth.

7. The carriage *M*, provided with the box

ing N, in combination with the rocker-shaft O, having the hinged fingers Q Q' on one side, which project into the shaft and embrace the plunger P at its inclined faces Q'', substantially as and for the purpose herein shown.

8. The carriage M, provided with the boxing N, in combination with the rocker-shafts O O, having the stationary diverging fingers R R on one side and the hinged fingers Q Q' on the opposite side, which project into the shaft and embrace the plunger P at its inclined faces Q'', substantially as and for the purpose herein shown.

9. A rocker-shaft, O, having within it the plunger P, provided with the inclined faces Q'', and the operating-lever P', in combination with the hinged embracing-fingers Q Q', substantially as and for the purpose set forth.

10. In broom-machines, a rocker-shaft having on one side stationary diverging fingers and on the opposite side hinged fingers, and the plunger having inclined faces for operating the embracing inner ends of the hinged fingers, as shown, for clamping wire, substantially as specified.

11. In broom-machines, the diverging fingers R R, secured to the rocker-shaft O on a

movable carriage, in combination with the die-heads L L', having grooves to receive tie-wires, substantially as herein shown.

12. In broom-machines, the hinged fingers Q Q' and the plunger P, having the inclined faces Q'', on a movable carriage, in combination with the die-heads L L', having grooves to receive tie-wires, substantially as and for the purpose specified.

13. The carriage M, having the boxing N and latch or catch T', in combination with the rocker-shaft O, having the head S, provided with the oppositely-disposed apertures S' at right angles to the fingers R Q Q', substantially as herein shown.

14. The carriage M, in combination with the links V V, the cross-lever U, having the arms U', the joint W, link W', arm X, rod X', and lever X'', substantially as herein shown.

In testimony that I claim the foregoing I have hereunto set my hand, this 27th day of March, A. D. 1882, in the presence of witnesses.

SAMUEL P. FRALEY.
